UNITED STATES PATENT OFFICE.

PHILIP A. REUTTER, OF WATERBURY, CONNECTICUT, ASSIGNOR TO SCOVILL MANUFACTURING COMPANY, OF WATERBURY, CONNECTICUT, A CORPORATION OF CONNECTICUT.

VANITY CASE.

Application filed January 15, 1925. Serial No. 2,487.

This invention relates to certain improvements in small boxes or cases used for carrying cosmetics and commonly known as vanity boxes.

5 Certain types of these vanity cases are designed to carry powder and rouge, either loose or in compact form, and a mirror or mirrors. Where two kinds of cosmetic are used and a plurality of mirrors, these boxes 10 are usually what are known as three part boxes, that is, there is a bottom, a cover and an intermediate compartment, these parts being generally hinged together and the intermediate compartment either carrying a 15 cosmetic, or a cosmetic and a mirror, or two mirrors. To make a secure and attractive construction, means are provided for holding the intermediate compartment in position and a common form of such means is 20 to provide a rib on this partition against which the cover and bottom telescope to make an attractive box. The telescoping parts are inset to form a shoulder. These 25 boxes are made of light metal and this setting weakens the box. Furthermore, the provision of the rib on the metal compartment requires an undesirable thickening of the box.

It is the special object of the present invention to produce a three-part box in which the rib on the center compartment is omitted and the cover and bottom abutted when in closed position outside the center compartment and at the same time are shaped so 30 as to hold the center compartment firmly in position when the parts are closed, thus doing away with the necessity of insetting and, therefore, weakening any of the members. A further object of the invention is to produce a box which, by the omission of this 35 rib, enables the production of a thinner box and, therefore, a box of more attractive and pleasing appearance.

With these and other objects not specifically referred to, the invention consists in certain novel parts, combinations and arrangements which will be described in connection with the accompanying drawings and the novel features pointed out in the claims 40 hereunto annexed.

Referring now to these drawings:

Figure 1 is a face view of a vanity box embodying the invention.

Figure 2 is a rear view.

Figure 3 is a plan view showing the box 55 open.

Figure 4 is a diagrammatic side view.

Figure 5 is a vertical sectional view taken on the line 5—5 of Figure 1, in the direction of the arrow in that figure. 60

Figure 6 is a vertical cross-section taken on the line 6—6 of Figure 5 looking in the direction of the arrow, and

Figure 7 is a view on an enlarged scale of the left hand end of the box shown in Figure 6, showing the spring catch construction for holding the parts together. 65

Referring now to these drawings, the box will include a bottom 1, a center compartment 2 and a cover 3, these parts being pivotally associated on a hinge 4. The bottom 1, in the particular construction illustrated, carries a cosmetic which may be a rouge cake, this cosmetic being carried in a cup 5 supported in a plate 6 welded or otherwise secured to the inner surface of the bottom. The center compartment 2 carries a powder compact, not shown, supported on a base 7 which in turn is removably held in position by a refill clip 8 having holding projections 9. The center compartment also carries a reflecting surface, as a mirror 10, the center compartment having its bottom formed with a cut-out portion, the edges of the cut-out portion being slightly bent up as at 11 to afford a support for the articles carried in this center compartment. 70 75 80 85

The cover of the box 3 is provided with a second reflector in the form of a mirror 12, held in place by a bezel 13. 90

In accordance with the invention, the box is made so that the center compartment is securely held in position when the parts are closed, without the use of a rim or bead and, furthermore, the edges of the box are rounded so as to produce a box of thin appearance. As shown, therefore, the cover and bottom are concave, as indicated at 14 and 15, and the edges of the top and bottom telescope over the center compartment and abut against each other when the parts are in closed position, as is shown at 16, these edges having a gentle curve to the abutting point, as clearly shown in the figures. To effect a support for the center compartment, the edges of the center compartment are also rounded, as best shown at 17 in Figure 6, the curve of the center compartment being sub- 95 100 105

stantially that of the curve of the top and bottom members, so that when the parts are in closed position the top and bottom have a closed telescopic engagement with the center compartment, and due to the curve being the same the center compartment is firmly held between the cover and the bottom. Thus a neat and attractive box is provided and one in which the parts are not weakened by insetting any of the parts and a firm, rigid structure is provided.

The parts may be held in closed position by a spring catch 18 which is released by manually operable release 19.

15 While the invention has been shown and described in its preferred form, it will be understood that various changes may be made in the interior of the box and in the arrangement of the articles carried thereby, 20 and the invention is not, therefore, to be limited to the exact structure shown and described.

What is claimed is:

1. In a vanity box, the combination of a 25 bottom, a cover, both having similar convex walls, and an annular intermediate compartment hingedly secured in position and formed to support a mirror and a powder compact, and having a side wall conforming 30 in convexity to the bottom and cover, the walls of the bottom and cover bearing against the upper and lower edges of the wall of the compartment and abutting in frictional engagement with the compartment wall when 35 the box is closed.

2. In a vanity case or the like, a bottom supporting a cosmetic, a cover, a mirror in the cover, a center compartment open at the top and bottom, the bottom edges being in-turned to support a mirror, the walls of the bottom and cover being formed with a curve and abutting when the box is in closed position and the walls of the center compartment being formed on a similar curve and having a telescoping engagement with the walls of the bottom and cover.

3. In a vanity case or the like, a bottom supporting a cosmetic, a cover, an intermediate member having means for supporting a powder compact on one side and having 50 its opposite edges in-turned to support a mirror, the walls of the bottom and cover bearing against the upper and lower edges of the wall of the intermediate member when the box is closed and holding the member in 55 position.

4. In a vanity case or the like, a bottom supporting a cosmetic, a cover, an intermediate member having means for supporting a powder compact on one side and a mirror 60 on the other, the walls of the bottom and cover bearing against the upper and lower edges of the wall of the intermediate member when the box is closed, a spring catch 65 carried by the intermediate member and engaging the bottom and cover, and a manually operated release for the catch.

In testimony whereof, I have hereunto set my hand.

PHILIP A. REUTTER.
